UNITED STATES PATENT OFFICE.

PETER E. McCULLOUGH, OF HOPEDALE, MASSACHUSETTS, ASSIGNOR TO DRAPER COMPANY,
OF HOPEDALE, MASSACHUSETTS, A CORPORATION OF MAINE.

BOBBIN-DRIVING MEANS FOR ROTATABLLE SPINDLES.

No. 899,178.

Specification of Letters Patent.

Patented Sept. 22, 1908.

Application filed February 21, 1908. Serial No. 416,981.

To all whom it may concern:

Be it known that I, PETER E. McCULLOUGH, a citizen of the United States, and resident of Hopedale, county of Worcester, 5 State of Massachusetts, have invented an Improvement in Bobbin-Driving Means for Rotatable Spindles, of which the following description, in connection with the accompanying drawing, is a specification, like letters 10 on the drawing representing like parts.

This invention has for its object the production of novel and efficient means for retaining a yarn receiver or bobbin in position upon a rotatable spinning, twisting or similar spindle and driving the bobbin in unison with the spindle.

My invention is particularly adapted for use in connection with bobbins employed in automatic filling-replenishing looms, such 20 bobbins having a series of metallic spring rings encircling the head of the bobbin, to be engaged by holding means in the shuttle when the bobbin is inserted automatically therein.

25 I have so constructed and arranged the bobbin driving means in my present invention that the rings themselves are frictionally and tangentially engaged, to effect the rotation of the bobbin, thereby obviating 30 changes in the wood of the bobbin due to unequal wear, variations in temperature, moisture, etc.

By engaging the rings the frictional contact is increased, and inasmuch as the outer 35 circumference of the rings is engaged the tendency is to center them with relation to the spindle, thereby overcoming the action of centrifugal force, which would otherwise make the spindle run untrue if the rings 40 were materially non-centered, as sometimes happens.

In accordance with my invention the spindle has mounted upon it a laterally expansible cup-like member into which the head of 45 the bobbin enters, the said member frictionally and tangentially engaging the peripheries of the rings on the bobbin-head and thereby effecting a driving connection between the bobbin and spindle.

50 The bobbin is readily and easily applied to the spindle and the friction driving member, and is easily withdrawn.

The various novel features of my invention

will be fully described in the subjoined specification and particularly pointed out in the following claims.

Figure 1 is a side elevation of a rotatable spindle with driving means applied thereto embodying one form of my present invention, a bobbin being shown in operative position, the bobbin and spindle being broken out to save space; Fig. 2 is a vertical diametral section of the apparatus shown in Fig. 1; Fig. 3 is a top plan view of the spindle and bobbin driving means.

In the present embodiment of my invention the spindle 1, of usual construction, and reduced at its upper end at 2, Fig. 1, to enter the reduced bore at the tip of the bobbin, has fixedly attached to it a depending sleeve 3 70 provided at its lower end with a whirl 4, the upper end of the sleeve having a central hub 5 embracing the spindle, Fig. 2.

Upon the sleeve and surrounding the hub 5 I fixedly secure a circular bobbin-rest 6, recessed to fit the upper end of the whirl sleeve, as shown in Fig. 2, the bobbin-rest forming the bottom of a relatively deep cut, the circular wall of which is formed by a series of thin resilient or spring fingers 7, transversely 80 segmental, as shown in Fig. 3, and concentric with the spindle, the inner faces of said fingers being straight longitudinally.

In practice the bottom and side wall of the cup are integral, the fingers being formed by 85 longitudinally slitting the wall, as at 8, to make the cup laterally yielding or expandible, the inner diameter of the expandible wall being normally slightly less than the external diameter of the rings 9 on the head 90 10 of the bobbin.

When a bobbin is applied to the spindle the head 10 is pushed into the cup and against the rest 6, thereby insuring a fixed vertical position of the bobbin relatively to 95 the spindle, and the inner faces of the resilient fingers 7 frictionally engage the rings 9, as shown in Fig. 2, the cup being expanded slightly as the rings move over its inner surface during the seating of the bobbin.

A light yet firm and effective frictional engagement is thereby secured, constituting a friction drive or connection between the spindle and bobbin and insuring the rotation of the latter in unison with the spindle.

The inherent spring of the rings, coöper-

ating with the resiliency of the fingers forming the wall of the cup, assist in securing a good frictional engagement and driving connection.

5 The cup wall is in tangential engagement with the outside of the rings, and tends to center the rings with relation to the spindle obviating any tendency to make the spindle run untrue, even if the rings are considerably 10 off center. It will be seen by reference to Fig. 2 that as the driving contact is wholly external, and on the rings, any variations or irregularities in the head or bore of the bobbin are of no moment.

15 The head of the bobbin is held in the cup-like driving member from lateral displacement, and the structure is simple, strong and efficient.

Having fully described my invention, 20 what I claim as new and desire to secure by Letters Patent is:—

1. A rotatable spindle having an attached whirl, combined with a bobbin having a series of metallic rings encircling its head, 25 and a series of upturned, segmental and straight resilient fingers rotating with and surrounding the spindle, said fingers receiving between them the bobbin head and driv-

ing the same by frictional and tangential engagement with the peripheries of the rings. 30

2. A rotatable spindle having an attached whirl and a circular bobbin rest above the whirl, combined with a bobbin having a series of rings on its head, and a resilient, expandable annular wall rising from the bobbin rest, to receive the bobbin head and frictionally and tangentially engage the rings thereon, to effect a driving connection between the bobbin and spindle, the end of the bobbin head engaging the bobbin rest. 40

3. The combination, with a rotatable spindle, of a deep, longitudinally slotted cup rotatable therewith and having a thin, straight and resilient wall, to frictionally and tangentially engage the rings on a bobbin head when 45 inserted in the cup and thereby effect a driving connection between the bobbin and spindle.

In testimony whereof, I have signed my name to this specification, in the presence of 50 two subscribing witnesses.

PETER E. McCULLOUGH.
